UNITED STATES PATENT OFFICE

2,272,386

ATTACHMENT FOR CARBURETORS

Clayton B. Seymour, Chicago, Ill., assignor to
Hoof Products Company, a corporation of Illinois

Application January 5, 1939, Serial No. 249,438

11 Claims. (Cl. 123—119)

My invention relates to improvements in fuel control mechanism and similar devices.

My invention relates more particularly to a fuel control means which includes in combination a carburetor having a manual throttle valve and a governor mechanism having an automatically controlled governor valve.

Since the introduction of automatic speed control governors into widespread use upon trucks, busses and other vehicles driven by internal combustion engines, or even in connection with the use of speed control means on stationary internal combustion engines, certain problems have arisen by reason of the fact that under certain conditions of operation the flow of fuel into the internal combustion engine is controlled entirely by the automatic governor valve. In the fuel control means of which I speak it is customary to have a manually controlled throttle valve in the carburetor mechanism and an automatically controlled governor valve in the fuel intake conduit at a point between the carburetor valve and the intake manifold of the internal combustion engine. One type of governor to which I refer may be similar to that shown and described in the patent to Addison C. Hoof, No. 1,999,758 or any other similar type of suction or vacuum operated governors or mechanical governors. Due to the fact that standard carburetors for various types of vehicles provide a control for the fuel supply, which depends upon the manual manipulation of the throttle in the carburetor, it can be seen that when an automatic governor valve is disposed in the conduit to the manifold at a point between the carburetor and the manifold, under normal governing conditions the carburetor valve is normally in a wide open position. Thus any fuel supply control which is regulated by the mechanism in the carburetor alone is either inoperative or is operated without regard for the governed speed at which the flow of fuel is controlled by the governor valve, and without regard to the load on the engine.

One of the carburetors of the type of which I speak is that shown in the patent to W. N. Ewart, No. 1,961,747. According to the construction of this patent and a construction which is standard today on various makes of automobiles, the carburetor is provided with a metering rod or valve controlling a certain portion of the fuel supply to the engine and adapted to be moved into or out of an orifice to restrict or increase the size thereof in accordance with the manual manipulation of the carburetor

throttle valve. Thus, as I have previously mentioned, with a governor inserted between the carburetor valve and the manifold and with the governor valve in control of the fuel supply, the carburetor valve is normally open and as a result there is no regulation of the flow of fuel to the metering jet as there would be if the carburetor valve itself controlled the amount of fuel supply to the engine. I have also found that 10 there are times when the governor valve is not in control of the flow of fuel to the intake manifold and under these circumstances it is desirable that the carburetor valve be connected to operate the metering rod.

15 The principal object of the present invention is to provide an attachment for a carburetor capable of being operated in accordance with the pressures in the intake manifold of the engine to control the operation of the above mentioned metering rod.

20 A further object of the present invention is to provide an attachment for a carburetor capable of being operated in accordance with the pressures in the intake manifold of the engine 25 when the governor is in control of the flow of fuel to control the operation of the above mentioned metering rod, and also capable of operation by the carburetor valve during the time that the governor is not in control of the fuel supply.

30 A further object of the present invention is to provide an attachment of the type described 35 capable of being substituted in standard carburetors to effectively and accurately control the supply of fuel in accordance with the governed speed of the engine and the load that is required to pull.

35 A further object of the present invention is to 40 provide an attachment of the type described which is capable of use with a standard carburetor and which will control the supply of fuel through the metering jet in accordance with the requirement of the engine without regard to whether a governor is used or not.

45 Other objects and advantages will be more apparent from the following description wherein reference is had to the accompanying four sheets of drawings, upon which

50 Fig. 1 is a fragmentary side elevational view showing a portion of the engine manifold, a governor, and a carburetor with my improved attachment connected therewith;

Fig. 2 is a fragmentary plan view of the same parts shown in Fig. 1;

55 Fig. 3 is a fragmentary sectional view through

the carburetor, governor and manifold, taken generally on the line 3—3 of Fig. 2;

Fig. 3a is an enlarged fragmentary view of the metering rod and associated parts;

Fig. 4 is a cross-sectional view similar to Fig. 3 with the carburetor and governor valves in a changed position and with the governor valve in control of the speed of the internal combustion engine;

Fig. 4a is an enlarged fragmentary view of the metering rod and associated parts in the changed position which it assumes under the conditions shown in Fig. 4;

Fig. 5 is a fragmentary plan view of a modified construction of the invention;

Fig. 6 is a vertical sectional view of the same taken generally on the lines 6—6 of Fig. 5 and

Fig. 7 is a transverse sectional view of the same form of construction taken generally on the lines 7—7 of Fig. 5.

In the embodiment of the invention which I have chosen to illustrate, I have shown the usual carburetor C, manifold M and governor G disposed between the carburetor and the intake manifold. The carburetor is provided with the customary manual throttle valve 10 and the governor with the customary offset valve 12. The carburetor valve 10 is mounted upon a shaft 14 in the fuel conduit 16 of the carburetor. The shaft may have a link 18 connected to one end of the same which connects with a rod 20 that extends to the usual manual throttle control accelerator. The opposite end of the shaft 14 is provided with the usual link 22 attached to the connector rod 24 which extends to a rocker arm 26. The rocker arm 26 is adapted to operate the pump mechanism for quick acceleration according to the usual well known construction.

In carburetors of the type which I have mentioned, a metering rod 28 is usually provided connected for up and down movement to the rocker arm 26. With this construction the metering rod is raised or lowered in direct relation to the movement of the carburetor valve.

In the construction which I have provided I connect the upper end of the metering rod 28 to an arm 30 fixedly secured to a block 32 attached to the upper end of a piston 34. The piston 34 is capable of reciprocative movement in a cylindrical opening 36 formed in the cover plate 38 for the liquid fuel well 40 of the carburetor. In order to normally hold the piston 34 in a raised position in the opening 36, I provide a conduit 44 communicating with the opening 36 and extending outwardly to an enlarged boss 46. With a suitable connector bushing 48, I connect a conduit 50 to the opening. The conduit 50 may extend downwardly to a suitable connector bushing 52 which provides a connection with the intake manifold 54.

The metering rod 28, as previously mentioned, is connected to the rigid arm 30 of the piston 34 and may extend downwardly through a suitable bore 56 in an elongated bearing 58 formed in the cover 38. The metering rod 28 is formed with a plurality of different sized metering portions 29 which project into a reduced passageway 60 in a nut member 62 screw-threadedly mounted in the base of the bowl 40. The passageway 60 communicates through passageways 64 and 66 with the main jet 68 of the carburetor disposed in the usual manner centrally of the usual Venturi openings of the carburetor.

In order to keep the metering rod 28 aligned in the bearing 58 and axially in the opening 60,

I provide a spring member 70 having the parallel coils 70a secured about the nut member 62 and the upwardly tapered coils 70b terminating in a coil 70c of slightly larger diameter than the shank 28 and continuing upwardly in an outwardly tapered portion 70d. With this spring member it can be seen that the rod 28 will be normally, resiliently and yieldably held axially disposed in the opening 60, thus providing under all conditions a circular passageway about the portion 29 of the metering pin.

The governor valve 12 may be mounted upon the shaft 12a and connected in the usual manner to resistance means which may be of the type shown in the patent to Hoof mentioned hereinbefore, adapted to permit complete closure of the governor valve to a desired fuel conduit opening.

From the foregoing description it will be apparent that by removing the cover plate 38 heretofore found on carburetors of the type described and substituting the cover member which I have provided, together with its associated mechanism, I have provided a control for the metering rod attached directly to the manifold.

When the carburetor valve 10 is in an open position, such as shown in Fig. 3, and the governor valve is not in a governing position, the spring 42 will be sufficient to prevent the suction in the manifold from drawing the piston 34 down or moving the metering rod to its lowermost position. With the carburetor valve open and the governor valve partially closed and in a governing position, depending upon the load on the engine, suction below the governor valve in the intake manifold will overcome the spring 42 and draw the piston 34 down in the cylindrical opening 36. This will move the metering rod to its lowermost position or that shown in Fig. 4a, restricting the flow of fuel from the well 40. It will thus be obvious that as the governor valve swings back and forth from an open to a closed position, the metering rod will be moved up and down, controlling the supply of fuel in accordance with the position of the governor valve.

From the above description it will be obvious that with the attachment which I have provided that the position of the metering rod under normal road load conditions will depend entirely upon the pressure conditions in the intake manifold. It will also be obvious that while the provision of the unit which I have furnished becomes necessary when governors are employed, that it can also be used without the interposition of a governor and efficiently control the supply of fuel without regard to the manual operation of the foot throttle, depending upon the pressure condition in the intake manifold.

It is sometimes desirable even, when a governor is employed, to permit manual control of the position of the metering valve during that period when the governor valve is not in control of the fuel supply. Accordingly in Figs. 5, 6, and 7 I have shown a modified form of the construction wherein I have provided an arm 72 extending sideways from the usual rocker arm 26 which is pivotally mounted upon the screw member 74 and which is attached at its end to an accelerator plunger 76. The end 78 of the rocker arm 26 is attached in the usual manner to the connector rod 24 extending from the manual valve shaft 14.

By providing the arm 72 extending over the top of the piston 34 it can thus be seen that when the governor is not in control and the manual valve is opened to permit high speed, the arm 72 is raised to permit the spring 42 to raise the pis-

ton 34 and the metering rod 28. However, when the speed of the vehicle is lowered and the carburetor valve is moved to a closed position, the arm 72 will bear down upon the piston 34 and by this means move the metering rod downwardly in the well 40. It can thus be seen that at any time the vehicle is travelling at a governed speed the metering rod is under the control of the vacuum in the manifold and when the governor valve is not functioning due to the cooperation of the spring 42 and the arm 72, the metering rod at once comes under the control of the manifold carburetor valve.

While I have illustrated and described a specific embodiment of my invention, it will be apparent to those skilled in the art that changes and modifications may be made in the exact details shown and I do not wish to limit myself in any particular. Rather, what I desire to secure and protect by Letters Patent of the United States is:

1. Fuel control means for an internal combustion engine having an intake manifold including a fuel mixture conduit, a carburetor having a manual throttle valve in said fuel mixture conduit, and an automatically controlled throttle valve in said conduit between said manual valve and said intake manifold; including means operable by said manual throttle to regulate the supply of liquid fuel to said conduit in accordance with the throttle setting, and means operative when said automatically controlled valve is in control and operable by pressure in said manifold for varying the supply of liquid to a value between the flow determined by said throttle setting and a fixed minimum.

2. Fuel control means for an internal combustion engine having an intake manifold including a fuel mixture conduit, a carburetor having a manual throttle valve in said fuel mixture conduit, and an automatically controlled throttle valve in said conduit between said manual valve and said intake manifold; including means operable by said manual throttle to regulate the supply of liquid fuel to said conduit in accordance with the throttle setting, and means operative when said automatically controlled valve is in control and operable by pressure in said manifold for varying the supply of liquid to a value between the flow determined by said throttle setting and a fixed minimum, said means including a metering rod in said carburetor and a piston connected thereto and subject to the manifold pressure.

3. Fuel control means for an internal combustion engine having an intake manifold including a fuel mixture conduit, a carburetor having a manual throttle valve in said fuel mixture conduit, and an automatically controlled throttle valve in said conduit between said manual valve and said intake manifold; including means operable by said manual throttle to regulate the supply of liquid fuel to said conduit in accordance with the throttle setting, and means operative when said automatically controlled valve is in control and operable by pressure in said manifold for varying the supply of liquid to a value between the flow determined by said throttle setting and a fixed minimum, said means including a metering rod in said carburetor and a piston connected thereto and subject to the manifold pressure to move the metering rod in one direction and resilient means for moving the rod in an opposite direction.

4. The combination with an internal combustion engine having an intake manifold, a fuel

mixture conduit, a governor having an automatically balanced valve, a carburetor having a manual valve in said conduit, said carburetor having a liquid fuel well, a metering jet and a metering rod associated therewith and movable with respect to the jet, a cover for said fuel well, means on said cover connected to said metering rod for regulating the flow of fuel past said rod in accordance with the pressure in the intake manifold of said engine and resilient centering means in said carburetor fixedly disposed with respect to said jet and embracing said metering rod, said metering rod being freely axially movable with respect thereto.

5. The combination with an internal combustion engine having an intake manifold, a fuel mixture conduit, a governor having an automatically balanced valve, a carburetor having a manual valve in said conduit, said carburetor having a liquid fuel well, a metering jet and a metering rod associated therewith and movable with respect to the jet, a spiral spring member fixedly mounted with respect to said jet and surrounding said metering rod in guiding relationship and resiliently centering the same in said metering jet, a cover for said fuel well and means on said cover connected to said metering rod for regulating the flow of fuel past said rod in accordance with the pressure in the intake manifold of said engine.

6. In a carburetor for association with the intake manifold of an internal combustion engine, said carburetor having a manual throttle located in a fuel mixture conduit, means operable by said manual throttle to regulate the supply of liquid fuel to said conduit in accordance with the throttle setting, and means operable by pressure in the intake manifold for varying the supply of liquid fuel to a value between the flow determined by said throttle setting and a fixed predetermined minimum flow.

7. In a carburetor for association with the intake manifold of an internal combustion engine, said carburetor having a manual throttle located in a fuel mixture conduit, means operable by said manual throttle to regulate the supply of liquid fuel to said conduit in accordance with the throttle setting, a metering valve for controlling fuel flow to said conduit, means responsive to predetermined manifold vacuum conditions at all open positions of the throttle for shifting the metering valve to a fixed minimum flow restricting position, and additional means for shifting said metering valve in response to movement of the manual throttle.

8. In a carburetor for association with the intake manifold of an internal combustion engine, said carburetor having a manual throttle located in a fuel mixture conduit, means operable by said manual throttle to regulate the supply of liquid fuel to said conduit in accordance with the throttle setting, a metering valve for controlling fuel flow to said conduit, means responsive to predetermined manifold vacuum conditions at all open positions of the throttle for shifting the metering valve to a fixed minimum flow restricting position, and additional means for shifting said metering valve in response to movement of the manual throttle, said additional means comprising a lost motion connection whereby the metering valve is responsive to said first named means when said additional means is not in control.

9. In a carburetor for association with the intake manifold of an internal combustion engine, said carburetor having a manual throttle located

in a fuel mixture conduit, means operable by said manual throttle to regulate the supply of liquid fuel to said conduit in accordance with the throttle setting, a metering valve for controlling fuel flow to said conduit, means responsive to predetermined manifold vacuum conditions at all open positions of the throttle for shifting the metering valve to a fixed minimum flow restricting position, and additional means for shifting said metering valve in response to movement of the manual throttle, said first named means being operative at all times to locate the valve in any operative position between the position determined by the location of the manual throttle and said fixed minimum.

10. In a construction for internal combustion engine carburetors adapted for association with the intake manifold of an internal combustion engine, a unit comprising supporting plate means, a suction responsive member associated with said supporting plate and having a conduit leading therefrom for communication with the intake manifold of said internal combustion engine, means connected with said suction responsive means for attachment with a carburetor metering rod and operative to shift said rod to mini-

25 mum flow restricting position in response to predetermined manifold vacuum, a shiftable member mounted on said plate means for movement in response to movement of the carburetor throttle valve, and means on said shiftable member extending into operative relationship with said metering rod attachment means for determining the maximum open position of said metering rod independently of said suction means and in accordance with the degree of opening of the manual throttle.

11. In a carburetor construction having a fuel mixture conduit and a throttle, means for metering fuel flow, means connected with said throttle for holding said metering means in substantially minimum flow restricting position when the throttle is substantially closed and operable to permit movement of said metering means toward open position in accordance with 20 the degree of opening of the throttle, and vacuum responsive means responsive to manifold vacuum conditions for adjusting said metering means to a position between said position determined by the degree of opening of the throttle and fixed minimum position.

CLAYTON B. SEYMOUR.
